United States Patent Office

Des. 211,620
Patented July 2, 1968

211,620

RECEIVER FOR CARDIOLOGICAL DATA OR THE LIKE

Frank H. Stephens, Jr., Dunwoody, Ga., assignor to
Lockheed Aircraft Corporation, Burbank, Calif.

Filed Jan. 25, 1966, Ser. No. 767

Term of patent 14 years

(Cl. D83—1)

FIG. 1

FIG. 4

FIG. 2

FIG. 3

FIGURE 1 is a perspective view of a receiver for cardiological data or the like embodying my new design; FIGURE 2 is a top plan view thereof;

FIGURE 3 is an elevational view taken from one side thereof; and

FIGURE 4 is an elevational view taken from one end thereof.

The dominant features of the design reside in the portions shown in full lines.

I claim:

The ornamental design for a receiver for cardiological data or the like, substantially as shown and described.
